UNITED STATES PATENT OFFICE.

THEODORE MILLER, OF DETROIT, MICHIGAN, ASSIGNOR TO THE ART STOVE COMPANY, OF SAME PLACE.

DESIGN FOR A STOVE.

SPECIFICATION forming part of Design No. 24,558, dated August 13, 1895.

Application filed April 29, 1895. Serial No. 547,572. Term of patent 7 years.

To all whom it may concern:

Be it known that I, THEODORE MILLER, a citizen of the United States, residing at Detroit, in the county of Wayne and State of Michigan, have invented and produced a new and original Design for Stoves, of which the following is a specification, reference being had therein to the accompanying drawings.

A are the legs of substantially a flaring **Y** shape having a rococo ornamentation. The circular base immediately above the legs has the plain vertical ring or band C at the top and the rococo-ornamented outwardly and downwardly curved edging D, which latter at the points of intersection with the legs has the curved projections E, conforming to the upper face of the legs. On the base and directly above it is the plain cylindrical tank F, from the top of which projects the overhanging substantially-rectangular flange H. This flange has semicircular enlargements G at its corners and is preferably ornamented, as shown, with rococo and basket ornamentation.

F' indicates ornamented plate-shaped standards extending from the ring C to the flange

H at the front and rear. Rising from the enlargements G of the flange H are the ornamented arches H', the corner-posts of which have ogee outer faces, and within the arches are the window-frames, as shown. Overhanging the arches is the cap-ring I, of substantially the same configuration as the flange H and ornamented. Above the said ring I rises the beaded cylindrical combustion-chamber 35 casing, above which is the circular cap-ring K, ornamented by a conventional leaf-design, and on this ring is the top L, ornamented by leaf-openwork, as shown at M'. Centrally on the top is the usual top ornament M. 40

The leading features of the design are the configuration and ornamentation of the stove, as well as of the various parts thereof.

What I claim as my invention is—

The design for a stove, substantially as herein shown and described.

In testimony whereof I affix my signature in presence of two witnesses.

THEODORE MILLER.
